UNITED STATES PATENT OFFICE

2,170,461

COMBINATION PULLER

Ben Pepperdine, Chicago, Ill.

Application June 23, 1937, Serial No. 149,898

5 Claims. (Cl. 29—85)

The invention relates to improvements in combination pullers especially adapted for pulling grease retainers, truck axles, drive shaft pinions, generator pinions, gear sleeves, bushings and other parts from automobile wheels and other locations, the primary object of the invention being the provision of a simple construction of the character indicated which is highly efficient in use.

10 Another object of the invention is the provision of a construction of the character indicated so constructed and arranged as to be insertable into comparatively small openings.

Another object of the invention is the provision of a construction of the character indicated which is readily reversible so as to readily engage either rings or the like or nuts or the like.

Another object of the invention is the provision of a construction of the character indicated which is of simple design and neat in appearance.

Other objects will appear hereinafter.

The invention consists in the combinations and arrangements of parts hereinafter described and claimed.

The invention will be best understood by reference to the accompanying drawing forming a part of this specification and in which

Fig. 1 is a partial side view, shown partially in section, of a combination puller embodying the invention;

Fig. 2 an enlarged section taken substantially on line 2—2 of Fig. 1;

Fig. 3 an enlarged section taken substantially on line 3—3 of Fig. 1;

Fig. 4 an end view of the construction shown in Fig. 1;

Fig. 5 a view similar to Fig. 4 but showing the clamping arms retracted into the smallest possible space;

Fig. 6 a detail section taken through the clamping head of the construction; and

Fig. 7 a detail section showing one of the clamping arms reversed and arranged for engaging a nut or the like.

The embodiment of the invention illustrated in the drawings comprises a suitable guide rod 10 having a knurled ram 11 slidable thereon. At one end, the rod 10 is provided with a removable handle member 12 which is removably threaded on the end of the rod 10 and also constitutes an abutment against which the ram 11 strikes in manipulating the puller. At its inner end, the ram 11 is provided with a hexagonal socket 13 adapted and arranged to receive a

hexagonal abutment 14 formed on the rod 10 and whereby the ram 11 may be utilized as a handle member to hold the rod 10 against turning when desired.

At its end opposite the handle 12, the rod 10 is provided with an operating head 15 having three radiating rectangular slots 16 extending therethrough. Loosely arranged in each of the slots 16 is an elongated clamping arm 17 provided in one side with a notch 18 and at its other side with a leaf spring 19 cooperating, as best shown in Figs. 6 and 7, to lock each clamping arm releasably in its slot and permit of free rocking or swinging of each arm in its slot. By this arrangement it will be noted that the arms 17 may be readily removed and reversed in their slots by compressing the springs 19 sufficiently to release the notches 18 from the opposite sides of the slot, as indicated in Figs. 6 and 7, so as to render them capable of engaging a ring by being inserted therethrough or engaging a nut by being placed around the same, as will be readily understood.

Associated with the operating head 15 is a manipulating member 20 threaded to reversibly engage the threads 21 on the rod 10 and provided with an interior conical cam surface 22 adapted and arranged to contact with the rounded cam surface 23 on the inner ends of the arms 17 as best indicated in Fig. 6 and whereby said arms 17 may be readily forced apart to effect engagement with a ring or the like, as will be readily understood. Wrench holes 24 are provided as shown in the member 20 to facilitate turning of the same on the rod 10, a result which is also facilitated by the handle action of the ram 11, as explained above. At their ends, the arms 17 are provided with engaging shoulders 25 to facilitate the action of the puller, as will be readily understood, and the inner surfaces of said arms are chamfered or beveled at 26 to permit of said arms being brought closely together as indicated in Fig. 5, and whereby said arms may be inserted through a comparatively small opening.

When it is desired to utilize the puller for engagement with a wheel nut, collar, or the like, the handle 12 and ram 11 are removed from the rod 10 and the manipulating member 20 reversed on said rod as indicated in Fig. 7. The clamping arms 17 are also reversed in their notches 16 so that the rounded cam surfaces 23 are engaged and cooperate with a conical exterior cam surface 27 provided on the manipulating member 20 and whereby the clamping arms 17 may be readily

45

50

55

manipulated to engage around a wheel nut or the like, as will be readily understood by those skilled in this art.

When the clamping arms 17 have thus been engaged with an object to be pulled or removed, the ram 11 is utilized as a hammer by sliding it on the rod 10 to strike against the abutment handle 12 thereby imparting shock to the engaged part to facilitate its release and removal.

By this arrangement, a simple and effective construction is provided which is capable of being inserted into recesses of considerable depth; which, owing to the length of clamping arms possible, will have a considerable length of expansion; which, owing to the form of the clamping arms, will be capable of entering and operating in comparatively small recesses and openings; which requires no loose parts or attachments; which may be readily converted to engage either rings or the like and nuts or the like; and which is of simple design and neat in appearance. The specific form and arrangement of parts is a simple and effective one for the purpose.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. A device of the class described comprising an operating handle; an operating head on said handle having slots extending therethrough; a clamping arm extending loosely through each of said slots; a spring carried by and releasably locking each arm in its slot; and a reversible manipulating member threaded on said handle and having both an interior and an exterior conical cam surface one cam surface and the arms co-operating in a certain arrangement of each to move the arms in one direction and, upon reversal of said arms and manipulating member, the other cam surface and said reversed arms co-operating to move the arms in the opposite direction.

2. A device of the class described comprising an operating handle; an operating head on said handle having slots extending therethrough; a clamping arm extending loosely through each of said slots; a spring mounted on one side and there being a notch in the other side of each arm releasably locking it in its slot; and a reversible manipulating member threaded on said handle and having both an interior and an ex-

terior conical cam surface one cam surface and the arms co-operating in a certain arrangement of each to move the arms in one direction and, upon reversal of said arms and manipulating member, the other cam surface and said reversed arms co-operating to move the arms in the opposite direction.

3. A device of the class described comprising an operating handle; an operating head on said handle having slots extending therethrough; a clamping arm extending loosely through each of said slots; a spring mounted on one side and there being a notch in the other side of each arm releasably locking it in its slot; a reversible manipulating member threaded on said handle and having both an interior and an exterior conical cam surface one cam surface and the arms co-operating in a certain arrangement of each to move the arms in one direction and, upon reversal of said arms and manipulating member, the other cam surface and said reversed arms co-operating to move the arms in the opposite direction; and a ram slidable on said handle.

4. A device of the class described comprising an operating handle; an operating head at one end of said handle having three radially arranged rectangular slots extending therethrough; a clamping arm extending loosely through each of said slots; a spring mounted on one side and there being a notch in the other side of each arm releasably locking it in its slot; a reversible manipulating member threaded on said handle and having both an interior and an exterior conical cam surface one cam surface and the arms co-operating in a certain arrangement of each to move the arms in one direction and, upon reversal of said arms and manipulating member, the other cam surface and said reversed arms co-operating to move the arms in the opposite direction; a ram slidable on said handle and having a socket polygonal in cross-section at one end; and a polygonal abutment on said handle engaging said socket.

5. A device of the class described comprising an operating handle; a plurality of clamping arms reversibly mounted on said handle; and a reversible manipulating member threaded on said handle and having both an interior and an exterior conical cam surface one cam surface and the arms co-operating in a certain arrangement of each to move the arms in one direction and, upon reversal of said arms and manipulating member, the other cam surface and said reversed arms co-operating to move the arms in the opposite direction.

BEN PEPPERDINE.
